MODEL AIRPLANE LAUNCHING ANCHOR
William A. Gardella, 7428 Coolidge, Center Line, Mich.
Filed May 6, 1963, Ser. No. 273,289
8 Claims. (Cl. 46—78)

The invention relates to a novel and useful model airplane launching anchor and more specifically to an apparatus including means for retaining a model airplane in a stationary position on the ground while the motor of the airplane is operating and during the time the person who is to fly the airplane moves from the airplane, after starting the latter, to the center of the circle over which the airplane is to be flown. After the person who is to fly the airplane reaches the center of the circle and retrieves the handle of his "U-control" he is then ready to fly the airplane.

"U-control" airplanes are tethered on the ends of a pair of control cables which are utilized for moving and are operatively connected to movable elevator controls of the model airplane. The model airplane launching anchor of the instant invention includes a barrier-type of retaining member which is latched in an upstanding operative position for retaining the airplane stationary when the motor of the airplane is operating. However, the launching anchor includes latch means for releasing the barrier-type of retainer in order that it may move to an inoperative position and this latch means includes an operator which may be engaged and operated by the movable elevator controls of the model airplane. Thus, after the person who is to fly the airplane has moved to the center of the circle and has picked up the handle for the "U-control," he may actuate this control in a manner to operate the latch of the launching anchor thereby enabling the barrier-type of retainer to move to the inoperative position whereupon the model airplane, whose motor is operating, will then be free to move forward and take-off under the control of the operator.

Without a model airplane launching anchor such as the anchor disclosed herein, it is necessary for the person flying the model airplane to have a companion or a helper capable of manually holding the model airplane after its motor has been started and during the time the person who is to fly the airplane moves to the center of the circle and picks up the handle of the "U-control." Therefore, the launching anchor of the instant invention will eliminate the necessity of a helper and enable a model airplane enthusiast to fly his airplane without help from others.

It is the main object of this invention to provide a model airplane launching anchor including means by which a model airplane whose motor is operating may be retained in a stationary position until such time as the person who is to fly the airplane can move to the center of the circle and manipulate the movable elevator controls of the model airplane by means of the "U-control" handle.

Another object of this invention, in accordance with the immediately preceding object, is to provide a model airplane launching anchor including means by which it may be readily adapted so as to be utilized in connection with various types of model airplanes.

Still another object of this invention is to provide a model airplane launching anchor including latch means for retaining upright barrier-type retaining means in the operative position and including other than a rigid connection with the barrier-type retaining means thereby eliminating the possibility that vibration of the model airplane would accidentally release the launching anchor before the person who is to fly the airplane reaches the

2

center of the circle and can grasp the handle of the "U-control."

A final object to be specifically enumerated herein is to provide a model airplane launching anchor which will conform to conventional forms of manufacture, be of simple construction and easy to use so as to provide a device that will be economically feasible, long lasting and relatively trouble free in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURE 1 is a perspective view of the model airplane launching anchor shown in position for retaining the model airplane in a stationary position;

FIGURE 2 is a somewhat enlarged side elevational view of the embodiment illustrated in FIG. 1 with parts of the airplane being broken away;

FIGURE 3 is a top plan view of the embodiment illustrated in FIGURE 2;

FIGURE 4 is an enlarged fragmentary longitudinal vertical sectional view taken substantially upon the plane indicated by the section line 4—4 of FIGURE 3;

FIGURE 5 is an enlarged transverse vertical sectional view taken substantially upon the plane indicated by the section line 5—5 of FIGURE 3;

FIGURE 6 is an enlarged fragmentary longitudinal vertical sectional view taken substantially upon the plane indicated by the section line 6—6 of FIGURE 3; and

FIGURE 7 is a fragmentary side elevational view of a modified form of launching anchor, with parts of the launching anchor being broken away and shown in section.

Referring now more specifically to the drawings the numeral 10 generally designates the model airplane launching anchor of the instant invention which is shown comprising a barrier-type retainer for a model airplane generally referred to by the reference numeral 12, and preventing forward movement of the model airplane 12.

The model airplane 12 is of a conventional type and is provided with a small internal combustion engine or motor 14 having a propeller 16 mounted on its output shaft. The model airplane 12 includes a pair of movable elevator control surfaces 18 to which a pair of control cables 20 are operatively connected at one end. The other ends of the control cables 20 have a "U-control" handle 22 secured thereto and it is to be understood that the control cables 20 also comprise a means for tethering the model airplane 12 to the handle 22.

Conventionally, after the motor 14 has been started by rear portion of the airplane 12, an assistant will grasp the rear portion of the airplane 12 and perhaps one wing tip thereof while the operator of the airplane 12 moves to the center of the circle and picks up the control handle 22. After the operator of the airplane 12 is sure that the motor 14 is operating correctly and the control cables 20 are operatively connected to the control surfaces 18, he will give a signal to his helper or assistant whereupon the latter will release the airplane 12 enabling the latter to move forwardly under its own power and to take-off under the control of the operator.

The model airplane launching anchor 10 of the instant invention includes a base plate 24 having a plurality of anchoring pins 26 secured therethrough and depending downwardly therefrom for engagement with the ground 28 whereby the base plate 24 will be maintained stationary on the ground 28.

A pair of elongated and generally parallel retaining members 30 are secured to the base plate 24 by means

of a pair of leaf hinge assemblies 32. Each of the leaf hinge assemblies 32 is provided with a leaf 34 which is secured to the base plate 24 in any convenient manner such as by fasteners 36. In addition, each leaf hinge assembly is provided with a second leaf 38 which is secured to the corresponding retaining member 30 in any convenient manner such as by fasteners 40. The retaining members 30 are, by means of the hinge assemblies 32, pivotally secured at corresponding end portions to the base plate 24 for rotation about generally aligned axes that generally parallel the medial plane of the base plate 24 and extend transversely of the latter.

As can best be seen from FIGURES 1 and 2 of the drawings the retaining members 30 are adapted to be disposed on opposite sides of the fuselage 42 of the airplane 12 and to engage the leading edges 44 of the stabilizer airfoil members 46 which project outwardly from opposite sides of the rear end of the fuselage 42. The stabilizer airfoil members 46 are provided with the movable control surfaces 18.

An operator bar 50 is pivotally secured to the base plate 24 at one end by means of a pivot fastener 52 secured through the operator bar 50 and the base plate 24. An anti-friction washer 54 is disposed between the confronting surfaces of the operator bar 50 and the base plate 24. In addition, an abutment member 56 is secured to the operator bar 50 in any convenient manner such as by fasteners 58 and includes an upstanding abutment flange 60 for a purpose to be hereinafter more fully set forth. It will be noted that the free end of the operator bar 50 is mounted for movement toward and away from the axes of rotation of the retaining members 30 and that an arm assembly generally referred to by the reference numeral 62 is provided. The arm assembly 62 includes a first elongated section 64 and a second elongated section 66. A second abutment member 68 is secured to the second section 66 in any convenient manner such as by fasteners 70 and includes a retaining flange 72 engageable with the flange 60.

The second section comprises a leaf of a hinge assembly generally referred to by the reference numeral 73 whose one leaf 74 is fixedly secured to the base plate 24 in any convenient manner such as by fasteners 76. The other leaf 77 of the assembly 73 also comprises a first leaf of a second leaf hinge assembly 76. The second leaf 78 of the hinge assembly 76 is secured to the first section 64 of the arm 62 by means of suitable fasteners 80 and an abutment screw 82 is threadedly engaged through the end of the first section 64 overlapping the second section 66 and includes a free end portion 84 engageable with the mid-portion of the second section 66 for limiting swinging movement of the first section 64 in one direction relative to the second section 66.

The free or forward end of the first section 64 overlies the one of said movable control surfaces 18 as can be seen in FIGURE 3 of the drawings and from a comparison of FIGURES 3 and 4 it may be seen that actuation of this one movable control surface 18 so as to incline the latter rearwardly and upwardly relative to the airplane 12 by means of the handle 22 will bring the upper surface of said one surface 18 into engagement with the undersurface of the forward end of the first section 64. Then, continued movement of the control surface 18 upwardly to the position illustrated in phantom lines in FIGURE 2 of the drawings will swing the entire arm assembly 62 in a clockwise direction as viewed in FIGURE 2 of the drawings moving the flange 72 out of registry with the flange 60 thereby enabling the operator bar 50 to swing from the position illustrated in solid lines in FIGURE 3 of the drawings to the position illustrated in phantom lines in FIGURE 3 of the drawings and therefore the retaining members 30 swing from the upright positions illustrated in FIGURE 2 of the drawings to the generally horizontally disposed positions illustrated in phantom lines in FIGURE 3 of the drawings as they are connected to the

mid-portion of the operator bar 50 by means of an elongated flexible tension member 86 whose opposite ends are secured and knotted through the retaining members 30 as at 88, the mid-portion of the tension member 86 being passed through the eye member 88 projecting upwardly from the mid-portion of the operator bar 50. From FIGURES 1 and 3 of the drawings it may be seen that the base plate 24 has a slot 90 formed therein providing a handgrip portion 92 at the rear end of the base plate 24.

With attention now invited to FIGURE 7 of the drawings it may be seen that a modified form of launching anchor generally referred to by the reference numeral 96 may also be provided. The launching anchor 96 is substantially identical to the launching anchor 10 with the exception being that a slightly modified anchor bracket 98 is secured to the operator bar 100 thereof and includes an upstanding flange 102 similar to flange 60. In addition, the arm generally referred to by the reference numeral 104 of the anchor 96 is not an articulated arm and is pivotally secured to the base plate 106 by means of a hinge assembly 108. However, the arm 104 is provided with an abutment screw 109 which is threadedly secured therethrough and corresponds to the screw 82. The abutment screw 109 is adapted for engagement with the flange 102 in lieu of a flange corresponding to the flange 72. Thus, while the screw 82 may be utilized to adjust the effective positioning of the flange 72 carried by the arm 62, the screw 109 comprises a substitute for the flange 72 and may therefore be utilized to adjust the point of swinging movement of the arm 104 relative to the base plate 106 at which the arm 104 will be released from engagement with the operator bar 100.

As can be seen from FIGURE 3 of the drawings the axis of rotation of the arm 62 is slightly inclined relative to a transverse plane disposed normal to the longitudinal axis of the base plate 24. The resultant angular positioning of the arm 62 assures proper releasing of the arm 62 by the elevator control surface 18 in the event the airplane 12 is shifted to the left as viewed from behind due to the direction of pull from the control cables 20.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A model airplane launching anchor comprising a base plate, a pair of elongated generally parallel retaining members pivotally secured at corresponding end portions to said plate for rotation about generally aligned axes generally paralleling the medial plane of said base plate and swinging movement between lowered inoperative positions closely overlying said base plate and upstanding operative positions adapted to receive the fuselage of a model airplane therebetween with said retaining members engaging the leading edges of a pair of airfoil members projecting outwardly of opposite sides of said fuselage, an operator mounted on said base plate for movement between first and second positions, means operatively connecting said operator and said retaining members for movement of said retaining members between said operative and inoperative positions in response to movement of said operator between said first and second positions respectively, movable and releasable latch means supported from said base plate operable to retain said operator in said first position and therefore said retaining members against movement from said operative positions to said inoperative positions, said releasable latch means including means adapted to be engaged and moved by a movable control surface of said airplane to a position releasing said operator and thereby said retaining members for movement toward their inoperative positions.

2. A model airplane launching anchor comprising a base plate, elongated retaining means pivotally secured at one end to said plate for movement about an axis generally paralleling the medial plane of said plate and extending transversely of the longitudinal extent of said retaining means and movement between a lowered inoperative position generally paralleling said plate and an upstanding operative position adapted to engage the leading edges of a pair of airfoil members projecting outwardly of opposite sides of the fuselage of said airplane, an operator mounted on said base independently of said retaining means and for movement between first and second positions, means operatively connecting said operator and retaining means for movement of said retaining means between said operative and inoperative positions in response to movement of said operator between said first and second positions respectively, movable and releasable latch means supported from said base plate and operable to retain said operator in said first position and therefore said retaining means against movement from said operative position, said releasable latch means including means adapted to be engaged and moved by a movable control surface of said airplane to a position releasing said operator and thereby said retaining means for movement toward its inoperative position.

3. The combination of claim 2 wherein said operator comprises a member including a portion movable toward and away from said axis, said means operatively connecting said operator member and said retaining means comprising elongated tension means secured between said portion of said operator member and a free swinging portion of said retaining means.

4. The combination of claim 3 wherein said elongated tension means is flexible.

5. The combination of claim 2 wherein said operator comprises a member including a portion movable toward and away from said axis and in a plane generally paralleling the medial plane of said base plate, said means operatively connecting said operator member and said retaining means comprising elongated tension means secured between said portion of said operator member and a free swinging portion of said retaining means.

6. The combination of claim 5 wherein said releasable latch means comprises an elongated arm pivotally secured at one end to said base plate for rotation about an axis generally paralleling the first mentioned axis, coacting

means carried by a first free swinging portion of said arm and said portion of said operator member engageable with each other in one position of swinging movement of said arm to prevent movement of said operator member toward the first mentioned axis and releasable with each other upon movement of said arm from said one position, a second free swinging portion of said arm comprising said means adapted to be engaged by said movable control surface of said airplane for moving said arm from said one position and releasing said operator member.

5 7. The combination of claim 6 wherein one of said coacting means includes adjustable means engageable with the other of said coacting means and for adjusting the point of swinging movement of said arm relative to said base at which said arm will be released from engagement with said operator member.

15 8. The combination of claim 2 wherein said operator comprises a member including a portion movable toward and away from said axis and in a plane generally paralleling the medial plane of said base plate, said means operatively connecting said operator member and said retaining means comprising elongated tension means secured between said portion of said operator member and a free swinging portion of said retaining means, said releasable

20 25 latch means comprising an elongated arm pivotally secured at one end to said base plate for rotation about an axis generally paralleling the first mentioned axis, coacting means carried by a first free swinging portion of said arm and said portion of said operator member engageable with each other in one position of swinging movement of said arm to prevent movement of said operator member toward the first mentioned axis and releasable with each other upon movement of said arm from said one position, a second free swinging portion of said arm comprising said means adapted to be engaged by said movable control surface of said airplane for moving said arm from said one position and releasing said operator member, said arm member including adjustable means operable for varying the point of swinging movement of said arm relative to said base at which said arm will be released from engagement with said operator member.
